UNITED STATES PATENT OFFICE.

ERSKINE J. S. VAN HOUTEN, OF NYACK, NEW YORK.

DESIGN FOR A BOTTLE.

SPECIFICATION forming part of Design No. 19,052, dated April 16, 1889.

Application filed October 17, 1888. Serial No. 288,397. Term of patent 7 years.

To all whom it may concern:

Be it known that I, ERSKINE J. S. VAN HOUTEN, a citizen of the United States, residing in the city of Nyack, county of Rockland, 5 and State of New York, have invented a new and original Design for Bottles, of which the following is a specification, reference being had to the accompanying drawings, forming a part thereof.

10 In the drawings, Figure 1 is a perspective view, and Fig. 2 is a profile or sectional outline, of a bottle embodying my design.

The leading features of my invention consist in the particular shape, as shown in Fig. 15 2, of the salient angle at the widest portion or greatest diameter of the bottle, the long upper side of the bottle and the long neck extending upward from the upper side thereof.

A represents the bottle, having a long vertical neck, B, which at the point C is enlarged into the main body of the bottle. The main

upper surface, D, extends downwardly at an obtuse angle from the point C and terminates at the point E. The lower side surface, F, extends downwardly and inwardly from the 25 point E at right angles therefrom. The bottom G is formed at an obtuse angle to the lower side surface, F.

My bottle has a cut-glass stopper, S, which is cut with any number of surfaces thereon. 30

What I claim as new therein, and desire to secure by Letters Patent, is—

The design for bottles herein shown and described, the same comprising the main body A of said bottle, provided with a long neck, 35 B, a long upper side, C, as shown in sectional outline, and a short lower side, F, at right angles to the upper side, as set forth.

ERSKINE J. S. VAN HOUTEN.
